CLAIM

The ornamental design for a baking machine, as shown and described herein.

DESCRIPTION

FIG. 1 is a perspective view of a baking machine in accordance with principles of the present disclosure;
FIG. 2 is a front view thereof;
FIG. 3 is a rear view thereof;
FIG. 4 is a left view thereof;
FIG. 5 is a right view thereof;
FIG. 6 is a top view thereof; and,
FIG. 7 is a bottom view thereof.

The broken lines depict portions of the baking machine that form no part of the claimed design.
